UNITED STATES PATENT OFFICE

FRANCIS E. JINNETT, OF VENTURA, CALIFORNIA

PIPE CLEANING MACHINE

Application filed May 14, 1930. Serial No. 452,274.

This invention relates to pipe-cleaning machines, and has for an object the provision of a machine by means of which cleaning may be effected of pipes or similar objects, either in relatively short lengths or made up into a continuous relatively long pipe.

Another object is the provision of a pipe-cleaning device having a suitable prime mover associated therewith by means of which the pipe cleaner is actuated instead of being manually driven.

A further object is the provision of a pipe-cleaning device which is carried upon a suitable wheeled frame, the wheels of which are adapted to roll upon the surface of the pipe being cleaned, and at least one of the wheels is connected to the prime mover, so that the machine may be advanced along the pipe or other article being cleaned by power derived therefrom.

A still further object is the provision of a pipe-cleaning machine which is capable of cleaning a continuous elongated pipe while that pipe is disposed within a trench, i. e., without the necessity of removing a buried earth or other material within which the pipe may be embedded.

A more detailed object is the provision of a pipe-cleaning machine of the general character described, in which the cleaning element is in the form of an annular head adapted to encircle the pipe to be cleaned, and which is so coupled to the prime mover, that the reciprocatory, rotary motion of the head is effected about the pipe or other article being cleaned, so as to cause each of a plurality of scraping tools with which the head is provided, to be moved in scraping engagement with the pipe, thereby removing accumulated dirt, scale, rust, and paint, so as to prepare the exterior surface of the pipe for the application of a fresh coat of paint.

A still further object is the provision of a pipe-cleaning machine of this general character, which is of a relatively simple nature, and hence, which may be manufactured and

operated at a minimum cost, and yet which is capable of operating with a high degree of efficiency and with relative rapidity in cleaning the exterior surface of such articles as pipes, rods, and the like.

Another object is to so construct the cleaning head that it may be employed to effi-

ciently clean welded pipe as well as the seamless variety, in this manner overcoming

one of the disadvantages of prior pipe-cleaning machines, the normal operation of which is interfered with by the presence of

the rib or head which extends from end to end of each length of welded pipe.

The invention possesses other objects and

advantageous features, some of which, with

those enumerated, will be set forth in the

following description of the invention's par-

ticular embodiment which is illustrated in

the drawings accompanying and forming a

part of the specification.

Referring to the drawings:

Figure 1 is a top plan view of a pipe-

cleaning machine embodying the principles

of the present invention.

Fig. 2 is a side elevation, the direction of

view being indicated by the arrow 2 of

Fig. 1.

Fig. 3 is a front end elevation, the direc-

tion of view being indicated by the arrows

3 of Figs. 1 and 2. Portions of the figure

are broken away and shown in section.

Fig. 4 is a rear end elevation, the direction

of view being indicated by the arrow 4 of

Fig. 1.

Fig. 5 is an enlarged detail view taken

sectionally through one side of the cutter

head and one of the cutting tools thereof.

The plane of section may be assumed to have

been taken upon the line 5—5 of Fig. 3, with

the direction of view as indicated.

In terms of broad inclusion, the pipe-

cleaning machine of the present invention

comprises a framework having supporting

wheels associated therewith, adapted to rest

upon the top of a substantially horizontally

extending pipe, whereby the entire machine

is supported upon the pipe and may advance

therewith. The frame carries a prime

mover which, preferably is coupled to at

least one of the supporting wheels, so that the energy necessary to advance the machine, may be derived from the prime mover. The machine is equipped with a cutter head adapted to encircle the pipe to be cleaned, and is so coupled to the prime mover that it is moved in reciprocatory, rotary motion about the axis of the pipe being cleaned, with the result that the cutting or scraping tools carried by the head and pressed into engagement with the pipe, are caused to move in such a manner that accumulated scale, rust, dirt, paint and the like, are effectually removed. Preferably the cutter head is followed by a brush which is also so coupled to the prime mover, that the surface of the pipe which has previously been scraped, is thoroughly brushed so as to more efficiently cleanse the exterior surface of the pipe, and prepare it for the subsequent application of a fresh coat of paint.

Specifically describing that embodiment of the invention which at present appears to be the most practical, my pipe-cleaning machine comprises a frame indicated in its entirety at 6, and comprising longitudinally extending members 7 and 8 held in spaced, preferably parallel relative arrangement by means of a plurality of transversely extending members 9, 11, and 12. A pair of auxiliary, transverse members 13 and 14, serve as a support for a prime mover such as an internal combustion engine 16 of conventional design. The shaft 17 of the engine 16, is provided with a flywheel 18 and with a sprocket wheel 19 carrying a drive chain 21 which is also enmeshed with a driven sprocket wheel 22 carried by a shaft 23 journalled in bearings 24 and 26 which are rigidly mounted upon the side member 8 of the frame 6. Preferably the shaft 23 is in two axially aligned parts 27 and 28 adapted to be optionally engaged or disengaged through the expedient of a conventional clutch mechanism 29 which, inasmuch as its details of construction have no bearing upon the present invention, will not be described in detail herein other than to point out that it is capable of being operated by means of a manually movable lever 31 pivoted in a bracket 32 which also is carried by the side member 8, and that the lever 31 is provided with dogs 33 loosely disposed within an annular groove 34 in the movable portion 36 of the clutch mechanism 29. Hence, by moving the hand lever 31 in one direction, the clutch mechanism 29 may be disengaged, and by moving it in the other direction, it may be engaged to effect connection between the portions 27 and 28 of the shaft 23.

Bearings 37 and 38 carried by the transverse members 11 and 12 respectively, rotatably support a countershaft 39 upon which is mounted a driven sprocket 41 and two driving sprockets 42 and 43. The driven

sprocket 41 is connected to a driving sprocket 44, which is rigid with the portion 28 of the shaft 23, by means of a drive chain 46, so that when the clutch mechanism 29 is engaged and the motor 16 is in operation, the countershaft 39 and the driving sprockets 42 and 43, are rotated.

Axially aligned bearings 51, 52, and 53 are mounted upon the ends of the transverse members 9, 11, and 12 respectively, at one side of the frame 6, whereas similarly aligned bearings 56, 57, and 58, are mounted upon the opposite ends of these transverse members. Within these two groups of aligned bearings, shafts 59 and 61 respectively, are journalled the former carrying a driven sprocket 62 which is interconnected with the driving sprocket 42 by a chain 63, and the latter carrying a driven sprocket 64 which is connected with the driving sprocket 43 by means of a chain 66.

Front and rear axle shafts 67 and 68, are journalled in axially aligned bearings 69 and axially aligned bearings 71 respectively. Each of these axle shafts carries a pair of spaced wheels 72, the peripheries of which are of conical configuration, i. e., each wheel 72 is tapered so that the entire machine may be supported upon the pipe 73 which is being cleaned and advanced longitudinally there along with those portions of the wheels 72 which are in rolling engagement with the pipe 73, substantially conforming to the configuration thereof, as best illustrated upon Figs. 3 and 4. Preferably, means are provided for applying torque to at least one of the axle shafts, say the axle shaft 68, so as to effect advance of the entire machine along the pipe 73 by power derived from the motor 16. This may be accomplished by means of a bevel gear 74 rigid with the shaft 59 and enmeshed with a bevel gear 76 which is carried by a stub shaft 77 journalled in a vertically arranged bearing 78. To the lower end of the shaft 77, a disc 79 is rigidly secured, this disc being provided with a crank pin 81 upon which one end of a connecting rod 82 is journalled. A ratchet wheel 83 is made fast to the axle shaft 68; and a crank arm 84 is mounted for rotary movement about the axis of the shaft 68 adjacent the ratchet wheel 83. This crank arm 84 carries a pawl 86 adapted to engage the teeth of the ratchet wheel 83 so as to effect rotary motion of the shaft 68 when the crank arm 84 is turned in one direction about the axis of that shaft, but to permit return motion of the crank arm 84 without having any effect upon the rotation of the shaft 68. As will readily be understood, rotation of the disc 79 will effect reciprocation of the connecting rod 82, thereby causing the crank arm 84 to move backwards and forwards in rotary motion; with the result that the pawl 86 will periodically engage a tooth of the

ratchet wheel 83, and turn the axle shaft 68 and the wheels 72 associated therewith, causing the entire machine to advance. When the disc 79 has completed one-half a revolution, the crank arm 84 will be returned to starting position, permitting the pawl 86 to drop past another tooth of the ratchet wheel 83 upon completion of a full revolution of the disc 79, so that the next half revolution 10 will again cause advance of the machine.

That portion of the machine which effects scraping of the outside surface of the pipe 73, is a cutter head indicated in its entirety at 91. This head 91 comprises a plurality, 15 preferably a pair of arcuate sections 92 and 93, at each end of each of which a radially extending flange 94 is provided, whereby the sections 92 and 93 may be rigidly but releasably coupled together by means of bolts 20 96 and nuts 97, thus forming an annular head slightly larger than the pipe 73 to be cleaned. It is my intention that a different size of head 91 be provided for each diameter of pipe 73 to be cleaned.

25 As best shown upon Fig. 5, each section 92, 93 of the head 91, is channel-shaped in cross-sectional configuration, being composed of a semi-circular web 98 and opposed edge flanges 99. This construction is employed 30 so as to impart the greatest possible strength to the entire structure. The fact that the head 91 is composed of a plurality of releasably joined sections, permits mounting the machine to commence operation thereof at 35 any point in a line of piping, without the necessity of slipping the head 91 over an end thereof.

40 Preferably from each face of the head 91, a plurality of pins 101 extend; and a roller 102 is journalled upon each of the pins 101. The radius of each roller 102 is substantially equal to the difference between the outside radius of the pipe 73 and the radius measured from the center of the annular 45 head 91 to the circle which passes through the centers of all the pins 101; with the result that when the head 91 is assembled about the pipe 73, all the rollers 102 will be in tangential rolling engagement with the 50 pipe, the effect being to retain the head 91 coaxially upon the pipe 73, but to permit rotary motion of the head 91 with respect thereto.

55 The head 91 is provided with a plurality of sockets 103 at spaced intervals throughout the entire periphery of the head. Whereas these sockets may be arranged according to any desired plan, I prefer to distribute them not only about the periphery of the 60 head, but also at different points between the front and rear faces 104 and 106 respectively, of the head, as best shown upon Figs. 1 and 2. Within each of the sockets 103, a scraper or cutting tool 107 is mounted. Each 65 socket 103 is non-circular in cross-sectional

configuration, preferably rectangular; and the scrapers 107 are complementarily formed so that they can not rotate within their respective sockets 103. However, they are fitted sufficiently loosely within the sockets 70 103, to permit them to slide radially with respect to the cutter head 91. Each cutting tool 107 is provided with an extension 108 which passes loosely through an aperture 109 in the upper end of the associated socket 75 103; and a pin 111 is rigidly secured adjacent the extreme end of the extension 108 of each tool 107, so as to limit the inward motion of that tool, it being understood that a coil spring 112 is under compression between the outer end of the socket 103 and a shoulder 113 on the tool 107, so that the tool is continually urged radially inwards to press the cutting edge 114 thereof against the outer surface of the pipe 73. As best 80 shown upon Fig. 3, alternate cutting tools 107 are arranged with their cutting edges 114 facing in opposite directions so that one tool 107 operates while the head is moved in one direction, and the next tool operates 90 upon movement of the head in the opposite direction.

The means for producing reciprocatory, 95 rotary motion of the head 91 with respect to the pipe 73 which it encircles, is in the form of discs 116 and 117 rigidly mounted upon the forward ends of the shafts 59 and 61 respectively. Each disc carries a crank pin 118, 119 arranged eccentrically thereupon; and connecting rods 121 and 122 are 100 journalled at their upper ends upon the crank pins 118, 119 respectively. The lower ends of the connecting rods 121, 122, are connected with opposite sides of the cutter head 91; and the eccentric discs 116, 117 are 105 so arranged with respect to each other, that the connecting rod 121 starts moving downwards at the instant that the other connecting rod 122 starts moving upwards, so that by their combined action, reciprocatory rotary motion of the head 91 is effected when the countershaft 39 is rotated.

110 The means for connecting each of the connecting rods 121, 122 to the cutter head 91, comprises an extension 126 of one of the associated flanges 94. This extension is bifurcated, forming two fingers 127 and 128 (see Fig. 2) upon each of which a block 129, 131 is rigidly arranged. A cross-head block 133 is disposed between the blocks 129 and 131, and carries pins 134 and 136 which are journalled within suitable apertures in the blocks 129 and 131 respectively. The lower end of each of the connecting rods 121 and 122, extends through an enlarged aperture 137 in the associated cross-head block 133. A compression spring 138 is interposed 120 between a pin 139 carried by the connecting rod, and the top of the cross-head block 133; and another compression spring 141 is inter- 125 130

posed between the bottom of the cross-head block 133 and a nut and washer 142 and 143 respectively, at the extreme lower end of the connecting rod. Hence, the force which is applied to the cutter head 91 to effect rotation thereof, is exerted by the springs 138 and 141. Furthermore, a certain amount of vertical movement of the cutter head 91 with respect to the frame 6 of the machine, is permitted, thus compensating for any slight irregularities upon the surface of the pipe 73 with which the wheels 72 might come in contact. Without the provision of such compensating means, the engagement of one or more of the wheels 72 with such irregularities, might cause breakage of one or more of the cutting tools 107.

The machine is also provided with an annular brush indicated in its entirety at 146. The framework for this brush, is constructed similarly to the annular cutting head 91, in that it is composed of a plurality of arcuate sections 147 and 148, releasably but rigidly secured in annular arrangement by means of bolts 149 passing through radially extending flanges 151 and 152. This annular framework which is indicated in its entirety at 153, is also provided with rollers 154 journalled upon pins 156, to retain the framework 153 coaxially with respect to the pipe 73. A plurality of arcuately-shaped brushes 157, are mounted upon the interior surface of the framework 153, these brushes having preferably relatively heavy wire bristles 158 of such length that they come into scrubbing engagement with the exterior surface of the pipe 73. The framework 153 for the brushes 157, is also reciprocated in rotary motion, through the expedient of discs 161 and 162 carried by the after ends of the shafts 59 and 61 respectively, these discs having crank pins 163 and 164 respectively, connected to the annular frame 153 by connecting rods 166 and 167, each of which is connected to the annular frame 153 through the expedient of springs 168 and 169 bearing against the upper and lower surfaces of a cross-head block 171, which in turn is pivotally connected by pins 172 to blocks 173 carried by an extension 174 of one of the flanges 151, this structure being substantially the same as that previously described in connection with the manner of engagement of the connecting rods 121 and 122 with the cutter head 91.

Operation

The pipe-cleaning machine of my invention is placed in operative position upon the pipe 73 to be cleaned, with the wheels 72 resting upon the upper portion of the outside circumference of the pipe, it being understood that in the event the pipe is buried, it first must be uncovered. A cutter head 91 and a brush 146 of suitable diameter

to accommodate the particular size of pipe being cleaned, are then selected and mounted in operative position by disengaging the flanges thereof, placing them in position encircling the pipe 73, and then securely clamping them together, as will readily be understood. The connecting rods 121 and 122 should then be connected to the cutter head 91, and the connecting rods 166 and 167 connected to the brush frame 153.

The motor 16 should then be started in operation, and the clutch mechanism 29 engaged by proper manipulation of the operating lever 31. This will effect rotary reciprocation of the cutter head 91 and of the brush 146 because of their interconnection with the shafts 59 and 61. The rotary reciprocation of the cutter head 91 will cause the cutting tools 107 to move back and forth in arcuate paths, pressing their cutting edges 114 against the outside surface of the pipe 73, thereby effectually removing all encrusted dirt, rust, scale, blistered paint and the like. The material that is removed in this manner, from the exterior surface of the pipe, falls out of either the forward or after faces 104, 106 respectively, of the cutter head, or through holes 181 which are formed at the bottom of the lower semi-circular portion 93.

As previously explained, the machine will be slowly advanced in successive steps because of the reciprocation of the crank arm 84 carrying the pawl 86 which engages the ratchet wheel 83. Hence, the cutter head 91 will be continually moved along the pipe to bring fresh portions thereof, into proper relationship with the head 91 to be cleansed by the scrapers 107. This forward motion of the entire machine, will cause the brush 146 to travel over the same portions of the pipe which have previously been scraped; with the result that it serves to increase the efficiency of the cleansing operation.

Owing to the fact that the head 91 moves in reciprocatory motion instead of rotating in a single direction, my pipe-cleaning machine affords unusual convenience in cleaning welded pipe. Tubing of this class has a seam extending from end to end of each length, and a bead of welded metal covering the seam, this bead protruding from the exterior surface of the pipe. Hence, the bead interferes with the cutting or scraping tools of a cleaning machine wherein the cleaning head or analogous part rotates continuously about the pipe. However, in my machine, the parts may be so proportioned and arranged, one or more of the cutting tools 107 being omitted if need be, that the outside surface of the pipe is effectively scraped up to the bead on both sides thereof, but none of the tools 107 is required to pass over the bead.

It is to be understood that the details of

the invention as herein disclosed, are subject to alteration within the spirit or scope of the appended claims.

I claim:

5. 1. In a pipe-cleaning machine, a frame, rollers journalled thereon in position to support said frame upon the pipe to be cleaned, a motor carried by said frame, a cutter head, scraping means carried by said head and engaging said pipe, a shaft journalled on said frame and coupled to said motor to be rotated thereby, a crank pin rigid with said shaft, a connecting rod journalled on said pin, and resilient means coupling said rod to said head whereby rotation of said shaft effects reciprocatory rotary motion of said head about said pipe. 70
10. 2. In a pipe-cleaning machine, a frame, a cutter head, scraping means carried by said head and engaging said pipe, a shaft journalled on said frame, means for rotating said shaft, a crank pin rigid with said shaft, a connecting rod journalled on said pin, a flange extending rigidly from said head, a cross-head having pins journalled in said flange, and resilient means coupling said connecting rod to said cross-head whereby rotation of said shaft effects reciprocatory rotary motion of said head about said pipe. 80
15. 3. In a pipe-cleaning machine, a frame, rollers journalled thereon in position to support said frame upon the pipe to be cleaned, a motor carried by said frame, a cutter head, scraping means carried by said head and engaging said pipe, a shaft journalled on said frame and coupled to said motor to be rotated thereby, a crank pin rigid with said shaft, a connecting rod journalled on said pin, a flange extending rigidly from said head, a cross-head having pins journalled in said flange, and resilient means coupling said connecting rod to said cross-head whereby rotation of said shaft effects reciprocatory rotary motion of said head about said pipe. 90
20. 4. In a pipe-cleaning machine, a frame, a cutter head, scraping means carried by said head and engaging said pipe, a shaft journalled on said frame, means for rotating said shaft, a crank pin rigid with said shaft, a connecting rod journalled on said pin, a flange extending rigidly from said head, a cross-head having pins journalled in said flange, and resilient means coupling said connecting rod to said cross-head whereby rotation of said shaft effects reciprocatory rotary motion of said head about said pipe. 100
25. 5. In a pipe-cleaning machine, a frame, means for supporting said frame upon a pipe to be cleaned, a cutter head, means carried by said cutter head and engaging said pipe to effect cleaning thereof, a motor carried by said frame, means coupling said motor to said head for moving the latter, and yieldable means interposed between said coupling means to permit play between said head and said frame. 110
30. 6. In a pipe cleaning machine, a frame, means for supporting said frame upon a pipe to be cleaned, a cutter head, means carried by said cutter head and engaging said pipe to effect cleaning thereof, means for retaining said head in coaxial relationship with said pipe, a motor carried by said frame, means coupling said motor to said head for moving the latter, and yieldable means interposed between said coupling means to permit play between said head and said frame. 120
35. 7. In a pipe cleaning machine, a frame, means for supporting said frame upon a pipe to be cleaned, a cutter head, means carried by said cutter head and engaging said pipe to effect cleaning thereof, means for retaining said head in coaxial relationship with said pipe, a motor carried by said frame, means coupling said motor to said head for moving the latter, and yieldable means interposed between said coupling means to permit play between said head and said frame. 130
40. 8. In a pipe cleaning machine, a frame, means for supporting said frame upon a pipe to be cleaned, a cutter head, means carried by said cutter head and engaging said pipe to effect cleaning thereof, a plurality of rollers journalled on said head and engaging said pipe to hold the head in coaxial relationship with the pipe, a motor carried by said frame, means coupling said motor to said head for moving the latter, and yieldable means interposed between said coupling means to permit play between said head and said frame. 140
45. 9. In a pipe cleaning machine, a frame, means for supporting said frame upon a pipe to be cleaned, a cutter head, means connecting said cutter head to said frame, and resilient means interposed in said connecting means to permit play between said frame and said head. 150
50. 10. In a pipe cleaning machine, a cutter head adapted to encircle a pipe to be cleaned, a plurality of scrapers extending inwards from said head to engage said pipe, and means for oscillating said head in rotary motion about the axis of said pipe, said scrapers facing in opposite directions, whereby 160
55. 65. 5. In a pipe-cleaning machine, a frame, rollers journalled thereon in position to support said frame upon the pipe to be cleaned, a cutter head, scraping means carried by said head and engaging said pipe, a shaft journalled on said frame and coupled to said motor to be rotated thereby, a crank pin rigid with said shaft, a connecting rod journalled on said pin, and resilient means coupling said rod to said head whereby rotation of said shaft effects reciprocatory rotary motion of said head about said pipe. 170

certain of said scrapers operate when the head moves in one direction and the other scrapers operate when the head moves in the opposite direction.

5 In testimony whereof I have signed my name to this specification.

FRANCIS E. JINNETT.
